UNITED STATES PATENT OFFICE

163,502

LADY'S STOCKING

Abrasha Wilcher, Manchester, N. H., assignor to Melvin J. Gordon, Sadie Z. Gordon, and
Natalie G. Stone, doing business as Manchester
Hosiery Mills, Manchester, N. H.

Application December 13, 1950, Serial No. 13,414

Term of patent 14 years

(Cl. D47—7)

To all whom it may concern:

Be it known that I, Abrasha Wilcher, a citizen of the United States, residing at Manchester, New Hampshire, have invented a new, original, and ornamental Design for a Lady's Stocking, of which the following is a specification, reference being had to the accompanying drawings, forming a part thereof, in which—

The other side of the stocking is the same as the side shown.

I claim:

The ornamental design for a lady's stocking, as shown and described.

ABRASHA WILCHER.
